UNITED STATES PATENT OFFICE.

PAUL RAMY, OF BRUSSELS, BELGIUM.

METHOD FOR SECURING RAILWAY RAILS TO THEIR SUPPORTS.

Application filed August 20, 1924, Serial No. 733,178, and in Belgium August 27, 1923.

My invention relates to an improved method for securing railway rails to their supports the said supports being indifferently in the form of iron sleepers or in the form of wood sleepers as it is more generally the case for high traffic railways.

One object of my invention is to secure a railway track of high stability in which any injurious play of the rails on their supports will be avoided in an efficient and simple manner.

And a further object of my invention is to prevent any creeping of the rails on the said supports without danger of distortion or breakage of the rails.

As it is well known, it has already been suggested in the case of rails secured to iron sleepers to weld the rails to their sleepers. This method however did not give practically satisfactory results as indeed the welding of the rails to the sleepers had as a result to make the expansions and contractions of the rails impossible, thus causing distortions of the track and even rail-breakages. On the other hand, in the case of rails mounted on wood-sleepers, it has been suggested to combine with the rails and even to weld to the rails special anchoring or anti-creeping devices adapted to act as abutments against the lateral faces of the wood-sleepers to resist the longitudinal displacement of the rails when they tend to have play on their supports on account of the loosening of the spikes or screws which generally takes place very shortly under the repeated running over of the trains. Such devices however did not work satisfactorily the anchoring elements producing in a very short time, a hammering effect against the wood sleeper, which hammering effect results in all the inconveniences which are encountered in the usual methods of securing rails to their supports as soon as a little play exists between the rail flange and its support.

And it is a still further object of my invention to avoid all these inconveniences of the known methods of securing rails to their supports whilst providing simultaneously for a better attachment of the rails.

With these objects in view my invention essentially consists in the novel features which will be hereinafter fully described and pointed out in the appended claims.

Referring to the accompanying drawings which show several embodiments of my invention and also auxiliary means used in connection with my improved method.

Fig. 1 is a diagrammatic view of a railway track showing the rails and their supporting sleepers.

Fig. 2 is a side view of one of the rails and corresponds to a section taken on line A—B in Fig. 1, showing the method as applied to the fastening of a rail on iron-sleepers.

Fig. 3 is a view similar to Fig. 2 but showing the method as applied in the case of a rail mounted on wood-sleepers by aid of supporting saddles or tie-plates.

Fig. 4 is a view similar to Fig. 3 of a modification.

In Fig. 1 of the drawing I have shown two rails 1 mounted on supporting sleepers 2. According to my invention each rail is rigidly connected to a number of sleepers in the central part of its length only, at the place where the expansion and contraction effects are particularly reduced, while on the contrary the parts of the rail located on both sides of the said number of sleepers are adapted to slide longitudinally to a certain extent on the corresponding sleepers or supports so as not to interfere with the expansion and contraction effects in the said parts of the rail. Consequently the rail is bodily connected and forms a single block or body in its central part with a number of sleepers and the said body prevents any creeping of the rail in the direction of the traffic on account of its large sliding surface and of its anchoring in the body of ballast or road-bed whilst the ends of the rail on both sides of this anchoring block or body may slide on their supporting sleepers so as to avoid any distortion of the rail which could otherwise result from an excessive resistance to the expansion or contraction-strains. Such a method is shown in Fig. 1, in which the sleepers 2 are divided into three groups on the whole length of the rail. The central group 3 comprises a number of sleepers 2 supporting the rail in its central part at same distance from its extremities whilst the groups 4 and 5, comprise the sleepers supporting the rail in its parts adjacent to the extremities.

According to my invention in order to prevent the creeping of the rails on the sleepers 2 and to provide nevertheless for the expansion or contraction of the rails, so as to avoid any distortion which could be injurious to the rails, the said rails are bodily connected to the sleepers of the central group 3 so as to form with these sleepers a single block or body; on the contrary they are fixed to the

sleepers of the end-groups 4 and 5 so as to be able to slide longitudinally on the said sleepers in case of expansion or contraction.

The solidarity of the rails, in their central part, with the sleepers of the central group 3 may be secured in various ways according to the mounting of the rails on the sleepers.

Fig. 2 shows the method which is used in 10 the case of iron-sleepers 6. In this case, the rail 1 is welded at 7 to the sleepers 6 of the central group 3 and it is attached to the sleepers of groups 4 and 5 by aid of bolts 8 cooperating with clips 9 under which the rail 15 is allowed to slide longitudinally.

In these conditions, the solidarity of the rail, with the sleepers of the central group 3 is secured by welding whilst the longitudinal displacement of the ends of the rails is 20 obtained by the sliding of the rails under the clips.

If the rails are mounted on wood sleepers 10 by aid of saddles 11 as shown in Fig. 3, two cases are to be considered. In the first 25 case, the rail 1 is welded only to the saddles 11 corresponding to the central group 3 of the sleepers but is attached to the saddles 11 corresponding to the end-groups 4 and 5 of the sleepers by means similar to those shown 30 in the example of Fig. 2.

In such conditions, the rail will form a single block or body with the central group of sleepers provided that the saddles 11 are attached without play to the said sleepers.

35 This is obtained by attaching the saddles 11 to the sleepers 10 by aid of screws 12 passing through holes 13 in the saddles, these holes corresponding exactly to the diameter of the screws or being provided with clamping sleeves 14 firmly compressed between the screw of the bolt and periphery of the hole provided in the saddle. It may be of wood or compressed paper, fibre, bakelite, a mixture of fibres or wood wool suitably compressed and agglomerated or of any other 45 suitable substances. It may also be formed of metal for instance of lead or of an alloy of metals, it may be split so as to be elastic and to adjust itself as exactly as possible. By

50 using sleeves of this kind the supporting saddles are locked on the sleepers and the solidarity of the rail with the sleepers is secured in its central part by the welding of the rail to the saddles whilst the freedom of 55 expansion and contraction of the ends of the rail is possible by attaching the rail to the saddles by aid of bolts allowing the longitudinal sliding of the rail relatively to the corresponding saddles.

50 In the second case, the rail is welded to all the saddles or tie-plates but the saddles which are mounted on the sleepers of the central group 3 only are provided with holes having the same diameter as the spikes or screws 65 so as to be bodily connected to the sleepers

whilst the saddles or rail-chairs which are mounted on the sleepers of the end groups 4 and 5 are provided with holes having a diameter larger than the diameter of the screws or bolts as shown in Fig. 4 or with elliptic 70 holes the major axis of which is parallel to the axis of the rail so as to allow the saddles or chairs to slide on the sleepers when the said saddles are dragged away by the expansion or contraction of the rail.

The same result may also be secured as shown in Fig. 4 by providing the saddles corresponding to the central group 3 of sleepers with a clamping sleeve 14 whilst the saddles corresponding to the end groups of sleepers 80 4 and 5 are mounted without clamping sleeves and are provided with holes 15 having a diameter larger than the diameter of the screw or bolt passing therein.

When all the saddles or rail-chairs 11 are 85 welded to the rail, the length of the saddles or chairs corresponding to the end groups 4 and 5 of sleepers (Fig. 4) will preferably be somewhat greater in the longitudinal direction of the track than the width of the sleeper 90 at the place of bearing of the saddle or chair. It is even advisable that the saddle or chair slightly exceed the width of the sleeper in such a manner that if the saddle or chair becomes incrusted in the sleeper, it will nevertheless be allowed to slide on the sleeper without being prevented therefrom by any projection formed by the wood of the sleeper.

When the track is laid with broken joints, 100 the above described methods may be applied to each line of rails separately.

In practice the welding of the rail to the saddles or chairs must be effected in observing certain cautions in order to avoid an injurious modification of the texture of the 105 metal of the rail flange under the action of the welding heat.

In the case of an attachment by aid of spikes the sleeve 14 instead of being cylindrical may be rectangular in shape and the hole in the sleeve instead of being circular in shape may be square, rectangular or polygonal in shape according to the section of the spike.

What I claim is:

1. A method of securing rails to their sleepers consisting in rigidly securing each rail at independent points in its central part to a series of sleepers whereby the creeping pressure is distributed over a large surface of ballast and in slidably securing the ends of each rail by ordinary means to the other sleepers.

2. A method of securing rails to their sleepers consisting in welding each rail at independent points in its central part to a series of sleepers whereby the creeping pressure is distributed over a large surface of ballast and in slidably securing the ends of each rail by ordinary means to the other sleepers.

3. A method of securing rails to their sleepers, one rail of a pair being in staggered rela-

tion to the other, consisting in rigidly securing each rail at independent points in its central part to a series of sleepers, the sleepers arranged under the ends of each rail being slidably secured by ordinary means to the said rail and the sleepers rigidly secured to the central portion of one rail being secured by ordinary means to the ends of the opposite rail so that such ends will be capable of sliding with respect thereto.

4. A method of securing rails to their sleepers, one rail of a pair being in staggered relation to the other, consisting in welding each

rail at independent points in its central part to a series of sleepers, the sleepers arranged under the ends of each rail being slidably secured by ordinary means to the said rail and the sleepers welded to the central portion of one rail being secured by ordinary means to the ends of the opposite rails, so that such ends will be capable of sliding with respect thereto.

In testimony whereof I have affixed my signature.

PAUL RAMY.
